CLAIM

The ornamental design for a combined radio, tape recorder, camera, binoculars, clock, calculator, compass and flashlight, as shown and described.

DESCRIPTION

FIG. 1 is a rear elevational view of a combined radio, tape recorder, camera, binoculars, clock, calculator, compass and flashlight showing my new design;

FIG. 2 is a front elevational view thereof, shown with the front compartment in an open position;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a top, front and left side perspective view thereof.

FIG. 1.

FIG. 2.

FIG. 3.

FIG. 4.

FIG. 5.

FIG. 6.

FIG. 7.
